US0D1048011S

(12) **United States Design Patent** (10) Patent No.: **US D1,048,011 S**
(45) Date of Patent: ** Oct. 22, 2024

(54) **CARD READER DEVICE**

(71) Applicant: **Ingenico Inc.**, Alpharetta, GA (US)

(72) Inventor: **Christopher Rotsaert**, Boston, MA (US)

(73) Assignee: **Ingenico Inc.**, Alpharetta, GA (US)

(**) Term: **15 Years**

(21) Appl. No.: **29/881,558**

(22) Filed: **Jan. 3, 2023**

(51) LOC (14) Cl. **14-02**

(52) U.S. Cl.

(57) **CLAIM**

The ornamental design for a card reader device, as shown and described.

DESCRIPTION

FIG. 1 shows a front view of the card reader device;
FIG. 2 shows a right side view of the card reader device;
FIG. 3 shows a left side view of the card reader device;
FIG. 4 shows a top view of the card reader device;
FIG. 5 shows a bottom view of the card reader device;
FIG. 6 shows a back view of the card reader device;
FIG. 7 shows a first perspective view of the card reader device showing portions of the front, left side, and bottom; and,
FIG. 8 shows a second perspective view of the card reader device showing portions of the back, right side, and bottom.

1 Claim, 6 Drawing Sheets
